PAPER CLAMP

Application filed February 10, 1931. Serial No. 514,851.

This invention relates to improvements in clamping devices, and pertains particularly to a clamp designed for securing papers together.

5 The primary object of the present invention is to provide a simple but strong and durable clamp which may be easily and quickly roughly adjusted to the proper size for holding a body such, for example, as a 10 number of paper sheets or the like, and which may then be drawn to a final tight grip upon the body by a novel securing means which also acts to retain the clamp in gripping condition.

15 Another object of the invention is to provide a clamp which will as efficiently grip and hold one or two sheets of paper as a stack of substantial thickness.

The invention broadly contemplates the 20 provision of a pair of relatively long members crossed and pivotally connected intermediate their ends, one of the members being formed to provide an arcuate toothed surface concentric with the pivotal connection between the members, which toothed surface is engaged by a dog pivotally mounted upon the adjacent other member. The 25 pivotal mounting for this dog is in the form of an eccentric with which a latch is connected so that by depressing the latch the dog will be forced forwardly and will impart a slight oscillatory movement to the member with which it engages at its free end. Each of the members is provided with a 30 laterally extended finger at its free end and the fingers of one member are disposed in opposed relation to the fingers of the other member so that when the members are oscillated in one direction these fingers come together to grip a sheet or other body, or a 35 number of sheets, therebetween.

The invention will be best understood 40 from a consideration of the following detailed description taken in connection with the accompanying drawings forming part of this specification, with the understanding, however, that the invention is not confined to any strict conformity with the showing of the drawings but may be changed or modified so long as such changes or modifications

mark no material departure from the salient features of the invention as expressed in the appended claims.

In the drawings:

Figure 1 is a view in side elevation of the 55 clamp embodying the present invention.

Figure 2 is a view in top plan of the same, a portion thereof being in section.

Figure 3 is a view in side elevation of a portion of a modified form of the clamp 60 structure.

Figure 4 is a sectional view taken on the line 4—4 of Figure 3.

Referring more particularly to the drawings, wherein like numerals of reference indicate corresponding parts throughout the several views, Figure 1 illustrates the preferred form of the present invention.

The invention, as illustrated in this figure, 70 consists of two relatively long flat arms indicated by the numerals 1 and 2, which are disposed in crossed relation with their flat faces in contact. These members are crossed at points substantially midway between their ends and a pivot pin or rivet 3 connects them 75 together so that they may be oscillated on this pin to move the ends of the members relative to one another. Each of the members has at each end a laterally extending gripping finger or jaw 4, each of these jaws being of arcuate cross-section, as shown, and the convex faces of the jaws of one member are in opposed relation to the convex surfaces of the jaws of the other member so that upon oscillating the members in the proper manner 80 these opposed jaws may have their convex surfaces brought into contacting relation. By providing jaws of this cross-sectional design it will be seen that an ample contact surface is provided for engaging a body disposed 85 between the jaws, no matter whether the body is thick or thin.

One of the members as, for example the member 1 is enlarged arcuately at one edge and concentric with the pivot pin 3, as indicated at 5. This arcuate edge of the member 1 is formed to provide a series of teeth 6. The other arm or member 2 has pivotally mounted therefrom the outer face thereof, one end of a stud 7 which has formed integral 100

therewith an eccentric cam 8, one face of which is in contact with the arm or member 2 and prevents looseness or movement of the stud 7 in the aperture in the arm 2.

The cam 8 engages in an aperture in one end of a pawl 9, the other end of which engages the arcuate toothed edge portion 5 of the adjacent arm 1.

Secured to the stud at the outer end thereof is a lever 10 which, when the clamp jaws 4 are separated to their fullest extent, extends substantially parallel with the arm 1. A suitable spacing washer 11 may be located between the lever and the eccentric cam portion 8 of the stud so as to provide the necessary clearance between the pawl and lever.

With the foregoing description, taken in association with the accompanying drawings, it will be readily seen that in applying the clamp one side of one or a number of sheets or other articles is first located between the jaws 4 and the jaws may then be brought together to engage opposite faces of the article or articles therebetween by oscillating the arms 1 by means of the hand or fingers. After the jaws have in this manner been made to more or less firmly grip the articles therebetween a firm grip of the clamp upon the articles may be obtained by depressing the lever 10, which operation will shift the pawl 9 longitudinally and thus, through the engagement of its free end with the teeth 6, force the jaws into a firmer engagement with the bodies therebetween. This cam actuated pawl also serves to locate the jaws in gripping relation. In order to release the articles held between the jaws 4 it will be readily seen that the lever 10 is first swung upwardly or in the reverse direction after which the engagement of the pawl 9 with the teeth 6 will be sufficiently loose to permit of its being disengaged by the fingers.

In Figure 3 there is shown a slightly modified form of the structure above described. In this form of the invention the rotatable stud 12 has the eccentric 13 formed upon the outer end thereof and there is formed in this outer end a socket 14 in which may be engaged the correspondingly formed end 15 of a key 16. This key 16 takes the place of the lever member shown in the form first described, and by its use it will be seen that the rotation of the stud 12 and the eccentric cam 13 may be effected to shift the pawl 17 which is carried at one end upon the cam. This pawl, at its free end, engages the toothed arcuate portion 18 of one of a pair of arms 19, the same as does the pawl 9.

From the foregoing description it will be readily appreciated that with a clamp of the character herein described one or a number of papers or other flat articles may be easily, quickly and firmly gripped and held together, and the clamp may be readily released for the insertion or removal of sheets.

Having thus described our invention, what we claim is:

1. A clamp of the character described, comprising a pair of elongated members, a pivotal connection between said members remote from one end thereof, a jaw carried by each member, said jaws being designed to be brought into abutting relation, pawl and ratchet means adapted to shift said members and jaws relative to one another and secure them in a set relation, and cam means for actuating the pawl and maintaining it in shifted position. 70

2. A clamp of the character described, comprising a pair of elongated members, a pivotal connecting means between said members, a jaw carried by each member and adapted to be moved into engagement with the other jaw, an arcuately arranged series of teeth carried by one member concentric with the pivotal connection, a pawl carried by the other member and having engagement with said teeth, and cam means for shifting said pawl to effect movement of the member engaged by the free end thereof. 80

3. A clamp of the character described, comprising a pair of elongated members, a pivotal connecting means between said members, a jaw carried by each member and adapted to be moved into engagement with the other jaw, an arcuately arranged series of teeth carried by one member concentric with the pivotal connection, an eccentric cam carried by the other member, a pawl having an aperture receiving said cam and having one end engaging said teeth, and means for rotating said cam to effect movement of the pawl and the member engaged by the free end thereof. 90

4. A clamp of the character described, comprising a pair of elongated members, means for pivotally connecting the members together so that the free ends thereof may be moved relative to one another, a jaw carried at the free end of each member and projecting laterally therefrom, said jaws being of arcuate cross section and arranged to have the convex faces of those of one member brought into contact with the convex faces of those of the other member, and latching means for securing said members against relative movement after oscillating the same to bring the jaws against opposite faces of a body disposed therebetween. 100

5. A clamp, comprising a pair of elongated members crossed intermediate their ends, a pivot pin connecting said members, a laterally extending jaw at each end of each member, the jaws of one member being arranged to be brought into contact with the jaws of the other member, an arcuate series of teeth formed upon one member concentric with said pivot, a stud pivotally carried by the other member, an eccentric cam carried by said stud, a pawl having one end engaging said teeth and having an aperture therein re- 110

ceiving said cam, and means for oscillating said cam to actuate the pawl relative to the teeth engaged thereby.

6. A clamp, comprising a pair of elongated members crossed intermediate their ends, a pivot pin connecting said members, a laterally extending jaw at each end of each member, the jaws of one member being arranged to be brought into contact with the 10 jaws of the other member, an arcuate series of teeth formed upon one member concentric with said pivot, a stud pivotally carried by the other member, an eccentric cam carried by said stud, a pawl having one end engaging 15 said teeth and having an aperture therein receiving said cam, and a lever connected with said cam to effect oscillation thereof.

7. A clamp, comprising a pair of elongated members crossed intermediate their 20 ends, a pivot pin connecting said members, a laterally extending jaw at each end of each member, the jaws of one member being arranged to be brought into contact with the jaws of the other member, an arcuate series 25 of teeth formed upon one member concentric with said pivot, a stud pivotally carried by the other member, an eccentric cam carried by said stud, a pawl having one end engaging said teeth and having an aperture therein receiving 30 said cam, a key, and means for coupling the key with the outer end of the stud.

8. A clamp of the character described, comprising a pair of elongated members, a pivotal connecting means between said members, a jaw carried by each member and adapted to be moved into engagement with the other jaw, an arcuately arranged series 35 of teeth carried by one member and concentric with the pivotal connection, a pawl pivotally mounted on the other member and further mounted for longitudinal movement thereon, and means for shifting the pawl longitudinally of its supporting member against said teeth to effect movement of the 40 other member.

45 9. A pivot clamp of the character described, comprising a pair of elongated flat members arranged in crossed relation, pivotal connecting means between the members, a series of teeth formed along an edge of one member on an arc concentric with the pivot therefor, an elongated pawl pivotally mounted upon the other of said members against the outer face thereof and having an inturned 50 forward end in engagement with said teeth, said pivotal support for the pawl constituting a cam whereby longitudinal movement of the pawl may be obtained, a stud formed integral with said cam, and a lever mounted 55 upon said stud for effecting rotation of the cam.

In testimony whereof we hereunto affix our signatures.
